UNITED STATES PATENT OFFICE.

RONALD A. McCANN, OF SWISSVALE, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed January 8, 1923. Serial No. 611,289.

To all whom it may concern:

Be it known, that I, RONALD A. McCANN, a citizen of the United States, residing at Swissvale, in the county of Allegheny and 5 State of Pennsylvania, have invented certain new and useful Improvements in Railway-Traffic-Controlling Apparatus, of which the following is a specification.

My invention relates to railway traffic 10 controlling apparatus and particularly to apparatus of the type comprising a trackway trip which is capable of assuming two positions, one of which I will term the operative and the other the inoperative position. The trip is preferably moved to its 15 operative position by gravity, and to its inoperative position by suitable power or energy controlled by traffic conditions in advance of the trip. A function of the trip 20 is to shut off the propelling power or apply the brakes or both, in a railway vehicle, should such vehicle pass the trip when the latter is in the operative position. This is generally accomplished by locating the trip 25 adjacent the track and in the path of an arm carried by the vehicle, which arm operates apparatus provided for affecting the power or brake systems, or both, of the vehicle. More particularly my invention re- 30 lates to the trackway circuits and apparatus for controlling the energy whereby the trip is moved from its operative to its inoperative position.

The accompanying drawing is a diagrammatic view showing one form of railway traffic controlling apparatus embodying my invention.

Referring to the drawing, the reference 35 character 2 designates the rails of a railway over which traffic normally moves in the direction indicated by the arrow. These rails 2 are divided by insulating joints 1 into a plurality of track sections A—D, D—E, E—F, etc. Each section is provided with 40 a source of track circuit current, which as here shown is a secondary winding 3 of a track transformer designated by the reference character T with an exponent corresponding to the location, this secondary being connected across the rails adjacent the 45 exit end of the section. Each section is also provided with a track relay designated by the reference character R with an exponent corresponding to the location. This relay 50

is connected to the rails adjacent the entrance end of the section. Thus it will be seen that each track section is provided with a track circuit comprising a transformer secondary 3, the rails 2 of the section and a track relay R. 55

The primary of each transformer T is supplied with alternating current from a generator 6 through line wires 5.

A signal S^A is located at point A and controls traffic in sections A—D and D—E. 60 Another signal S^E is located at point E and is controlled by sections E—F and F—G, and a third signal S^F is located at point F and controls the two sections to the right of F, only one of which F—G, is shown in the 65 drawing. Each of these signals comprises a semaphore arm capable of assuming two positions and indicating stop or proceed depending on the position of this semaphore arm with respect to its mast. 70

A train stop K is located at point E, and, as shown in the drawing, comprises a magnet coil K² and a pivotally mounted trip K' controlled thereby in such a manner that when the coil K² is energized the trip K' 75 is moved into an inoperative position wherein it will not engage the train carried arm of the stop mechanism. When the coil is de-energized the trip is moved by gravity to the operative position wherein the trip 80 will engage the train carried arm of the stop mechanism. Since the train carried mechanism is not essential to the complete disclosure of my invention, I have omitted it from the drawing for the sake of simplicity. 85

Associated with track relay R^A is a line relay H^A, and associated with the track relay R^E is a line relay H^E. The line relay H^E is provided with a circuit which passes 90 from one terminal B of a source of energy not shown in the drawing through front contact 7—8 of relay R^F, wire 21, front contact 7—8 of relay R^E, wire 31, and the winding of relay H^E to terminal C of the energy source. This circuit is closed only 95 when relays R^F and R^E are energized. A similar control circuit is provided for relay H^A which circuit is closed when relays R^A and R^D are energized. 100

The coil K² of the train stop K is normally energized through a circuit which passes from terminal B of a source of energy 105

not shown in the drawing, through wire 19, front contact 16—17 of relay H^E , wire 23, and coil K^2 of train stop K to the other terminal C of the energy source. This circuit 5 is, of course, closed only when the relay H^E is energized. A retaining circuit is also provided for the coil K^2 which circuit passes from one terminal B of a source of energy not shown in the drawings, through back 10 contact 7—13 of relay R^D , wire 24, a contact 32 which is closed only when the trip is in the inoperative position wire 25, coil K^2 , and back to the other terminal C of the energy source. This circuit is closed only 15 when the relay R^D is de-energized. A third circuit is provided for the stop, which circuit passes from one terminal B of a source of energy not shown in the drawing, through front contact 7—8 of relay R^A , 20 wire 28, front contact 9—11 of relay R^D , wire 26, back contact 16—18 of relay H^E , wire 23, coil K^2 and back to the other terminal C of the energy source. This circuit is closed only when relay H^E is de-energized 25 and relays R^A and R^D are both energized and serves to keep the trip in its inoperative position to allow reverse running, that is, contrary to the direction of traffic controlled by the signals.

30 Each of the signals S is preferably biased to its stop indication and provided with means controlled by its associated line relay for causing it to move to the proceed indication. Thus for example, the circuit for signal S^A passes from one terminal B of a 35 source of energy not shown in the drawing, through front contact 14—15 of its associated line relay H^A , wire 29 and the operating mechanism of the signal S^A to the other terminal C of the source. The circuit for signal S^E is the same as for signal S^A , and 40 includes a front contact 14—15 of its associated line relay H^E .

45 The operation of the system is as follows: Should a train enter section A—D traveling in the direction of the arrow, the relay R^A , being de-energized, will open the circuit of the associated line relay H^A , causing the signal S^A to move to the stop position. As the train passes into section 50 D—E, track relay R^D is de-energized, thus closing at contact 7—13 the retaining circuit for the stop K^2 . Then as the train enters section E—F it opens relays R^E and H^E , but the stop remains in the inoperative position until the rear of the train passes out of section D—E, this being due to the retaining circuit controlled by relay R^D . While this train is in block E—F relay R^D 55 is energized and relay H^E is de-energized, and so the stop is in the inoperative position. Now if a following train enters the block A—D, the relay R^A will be de-energized and the stop will assume the operative position because contact 7—8 of relay

R^A is open. As this train enters section D—E, relay R^D will be de-energized, thus closing contact 7—13, but the trip will not move to the inoperative position because contact 32 is open. As a result the trip will stop the train if it attempts to pass point E. Thus complete protection is afforded for following trains in normal direction of traffic. Also means are provided for automatically moving the stop to its inoperative position for reverse running. Thus, if relays R^A and R^D are both energized, and the relay H^E is de-energized by a train moving toward the left, the stop is energized through the back contact 16—18 70 of the relay H^E as explained above, and the stop is retained in the inoperative position after the train has passed into block D—E, by means of the retaining circuit through contact 32 and back contact 7—13 of relay R^D as in normal operation. But if either section A—D or D—E is occupied, the corresponding track relay will be de-energized, thus opening the clearing circuit for reverse 75 running through its front contact and the train will be stopped by the train stop which will then be in the inoperative position. 80

85 Although I have herein shown and described only one form and arrangement of railway traffic controlling apparatus, it is understood that various changes and modifications may be made therein within the scope of the appended claims without departing from the spirit and scope of my invention.

90 Having thus described my invention, what I claim is:

1. A railway traffic controlling system comprising a trackway trip, means controlled by traffic conditions in the rear of said trip for retaining said trip in its inoperative position and means controlled by said trip for preventing the said first means from moving said trip from its operative 95 to its inoperative position.

100 2. In combination, a trackway trip having an actuating mechanism and a contact which is closed only when said mechanism is energized, a relay controlled by traffic conditions in the rear of said trip; and a circuit for said actuating mechanism including a source of energy, the said contact, and a back contact on said relay.

105 3. In combination, a trackway trip comprising an actuating mechanism, a section of railway track in the rear of said stop, a second section of railway track in the rear of said first section, a relay controlled by traffic conditions in said first section, a second relay controlled by traffic conditions in said second section, a third section of railway track in advance of said stop, a third relay controlled by traffic conditions in said third section; and a circuit 110 for said actuating mechanism, including a 115

source of energy, a front contact of said first relay, a front contact of said second relay and a back contact of said third relay.

4. In combination, a trackway trip, a rail-way signal associated therewith and controlled by traffic conditions in advance, means controlled by traffic conditions in advance of said trip for moving the trip to its inoperative position, means controlled by traffic conditions in the rear of the trip for retaining the trip in its inoperative position, and means controlled in part by traffic conditions in advance and in part by traffic conditions in the rear of the trip for moving said trip to its inoperative position.

5. In combination, three successive sections of railway track, a track circuit for each section including a track relay, a track-way trip located at the junction of the second and third sections, a clearing circuit for said trip controlled by the track relay for the third section, a retaining circuit for said trip controlled by a back contact of the track relay for the second section and

by a contact which is closed only when the trip is in its inoperative position, and a reverse running clearing circuit for said trip controlled by the track relays for the first and second sections and by a contact which is closed when the track relay for the third section is de-energized.

6. In combination, a trackway trip, a forward and rear section of track, a track circuit for each section including a track relay, a clearing circuit for said trip controlled by the track relay for the forward section, a retaining circuit for said trip controlled by a back contact of the track relay for the rear section and a contact which is closed only when the trip is in the inoperative position, and a reverse running clearing circuit for said trip controlled by the track relay for the rear section and a contact which is closed when the track relay for the forward section is de-energized.

In testimony whereof I affix my signature.

RONALD A. McCANN.
